UNITED STATES PATENT OFFICE.

JAMES E. POTTS, OF CLEVELAND, OHIO.

HOT-WATER HEATER.

No. 901,828.

Specification of Letters Patent.

Patented Oct. 20, 1908.

Application filed July 29, 1907. Serial No. 385,996.

To all whom it may concern:

Be it known that I, JAMES E. POTTS, a citizen of the United States, and resident of Cleveland, county of Cuyahoga, State of Ohio, have invented certain new and useful Improvements in Hot-Water Heaters, of which I hereby declare the following to be a full, clear, and exact description, such as will enable others skilled in the art to which it appertains to make and use the same.

The objects of the invention are to provide a hot water heater, capable of great efficiency in use and in which all the parts are simple in construction, and are not at all liable to get out of order and in which all the circulating passages are readily accessible for cleansing them from mineral deposits therein or soot upon their exterior surfaces.

In this heater water tubes are utilized as grate bars, and a double circulating system conveys the water through these tubes to a manifold chamber in the front wall of the boiler setting. Inlet pipes also convey the water to a manifold chamber in the rear wall of the boiler setting from whence it is led through longitudinally arranged tubes about which the hot air and products of combustion from the burning grate circulate. These tubes communicate also with the front manifold chamber and the water heated by the tubes in the grate and longitudinal tubes passes into the heating circulation of the building.

The invention further consists in the combination and arrangement of the circulating passages and construction of the various details as hereinafter described, shown in the accompanying drawings and specifically pointed out in the claims.

In the accompanying drawings, Figure 1 is a longitudinal vertical section through the improved water heater; Fig. 2 is a front elevation thereof and Fig. 3 is a plan view of the grate. Fig. 4 is a detail horizontal section of one of the walls of the grate showing the staggered arrangement of the grate tube flanges to permit of giving them greater width and also of making them more accessible.

In these views 1 is the setting, 2 the bridge wall, 3, 3 are duplicate slightly inclined pipes through which the cold water is supplied to the heater, and which pass through the side walls of the fire box 5. The grate surface is obtained by means of the trans-

versely arranged horizontal circulating tubes 4, which connect with and form a communication between the pipes 3, 3, and these grate tubes extend between the bridge wall 2 and the front wall of the fire box 5. The pipes 3, 3 are then upwardly extended at 6 and enter the front manifold 7 at its lower end at 8.

The grate bars are horizontal but rise gradually one above the other in a stepped form, the front bar being the highest. The effect of which novel construction is to subject the water more evenly to the heat and to cause a more regular circulation from the increasing height of the bars.

Vertical branches 9 from these pipes enter the lower sides of the rear manifold chamber 10 and longitudinal tubes 11 connect the front and rear manifolds and form circulating passages providing communication between these manifolds.

To obtain as much heating effect as possible upon these longitudinal tubes from the products of combustion coming from the grate and passing out of the chimney stack 12, a fire brick partition 13 is laid upon the tubes at a suitable level. This partition does not cover the entire surface of the tubes but an opening 14 is left at the rear so that the products of combustion will first traverse the entire length of the tubes below the partition and then the entire length of the tubes above the partition until they arrive at the stack, thus insuring the action of the heated gases upon all parts of the tubes.

The tubes 11 are inserted in the inner walls of the manifolds, and the outer walls 15 and 15' of the manifolds are secured thereto by means of hinges 16 and 16' so that the outer walls can be swung back to enable the operator to have access to the tubes for cleaning away any sediment or mineral deposit left therein by the circulating water.

The front manifold is provided in addition to the inlet openings on its lower sides with the outlet opening 17 in the hinged front wall which leads to the house system S such as indicated in dotted line. A Y is provided to connect the circulating pipe S with the pipes 3, 3, at X.

The manifolds are preferably inserted in and form portions of the front and rear walls of the setting.

To enable the grate tubes to be readily removed from and to be attached to the circulating pipes, these pipes are provided with

laterally extending flanged nozzles N alternately long and short and the grate tubes are provided with flanges adapted to engage the flanges of the nozzles. This construction 5 is plainly shown in Figs. 3 and 4, the effect being to stagger or alternate the flanges in parallel planes so that a much greater width can be given to the flanges and much larger gaskets can be placed thereon, so as 10 to prevent the joints from leaking; than if the joints came opposite to each other.

In the figures are shown also, upper and lower perforated plates P supported upon the longitudinal circulating tubes, one above 15 and one below the level of the fire brick partition. These plates can be moved longitudinally along the tubes and will remove any insulating deposit therefrom such as cinders or soot. Long rods R attached to 20 the plates and passing through openings O in the rear wall of the casing serve as operating means therefor.

The swinging outer walls of the manifolds afford opportunity for readily cleansing the 25 inner parts of the longitudinal tubes, and the grate tubes being so attached as to be easily removed they can also be readily cleansed from any deposit therein.

The advantages of the double circulating 30 system of tubes in the fire box casing provides for unusual efficiency in action and use. The water is quickly heated and the rise of the hot water from the lower grate system assists in obtaining a quick flow 35 through the longitudinal tubes above.

The fire brick partition can be placed at any level determined to be the most efficient, or as many partitions can be used as desired, alternating the terminal openings.

40 Having described the invention what I claim as new and desire to secure by Letters Patent is:—

1. In a heating device, having a furnace setting, a fire box and bridge wall, the combination therewith, of duplicate inclined longitudinal water inlet pipes arranged one on each side thereof in said setting, a common inlet opening therefor, a horizontal series of transversely arranged grate tubes, connecting 45

50 said longitudinal pipes in front of the bridge wall, alternating short and long flanged nozzles upon said longitudinal pipes, flanges upon the ends of said tubes for attachment to said nozzles, said flanges being arranged 55 in staggered order to enable said grate bars

to be placed closely together, a front common chamber with which said longitudinal pipes communicate, said chamber being situated in the front wall of the casing and provided with a hinged front wall and having 60 an outlet at the upper end, and a rear chamber with which said circulating pipes communicate and pipes connecting said front and rear chambers.

2. In a heating device, provided with a furnace casing, and a fire box and bridge wall therein, the combination therewith, of a manifold chamber in the front wall, and a similar manifold chamber in the rear wall, 70 said chambers having swinging outer walls, 75 horizontal tubes connecting said manifolds, a horizontal partition mounted on said tubes intermediate between the upper and lower tubes, a lower system of transverse water tubes forming a grate in the fire box and 80 spaced closely together, longitudinal pipes in the sides of the casing with which said tubes communicate, flanged joints connecting said grate tubes and said circulating pipes, the flanges thereon being staggered in position, 85 connecting pipes between said longitudinal pipes and said rear manifold, connecting pipes between said longitudinal pipes and said front manifold, and a circulating pipe communicating with the front swinging wall 90 of said front manifold and with both said longitudinal pipes at the sides of said casing, substantially as described.

3. In a heating device, having a furnace setting a fire box and bridge wall, the combination therewith, of duplicate longitudinal water inlet pipes arranged one on each side thereof and inclined upwardly from the rear, a common water inlet therefor located in the rear thereof, a series of horizontal, transverse 95 grate tubes, communicating with said longitudinal pipes, and arranged in steps, the highest grate tube at the front end of said fire box, a common front chamber communicating with said longitudinal pipes, an outlet 100 at the upper end thereof, and a rear chamber communicating with the rear ends of said longitudinal tubes, and connecting pipes between said chambers above said fire box.

In testimony whereof I hereunto set my 105 hand this 13th day of July 1907.

JAMES E. POTTS.
